UNITED STATES PATENT OFFICE.

JAMES T. COWLEY, OF BOSTON, MASSACHUSETTS.

PNEUMATIC-DESPATCH-TUBE APPARATUS.

SPECIFICATION forming part of Letters Patent No. 687,201, dated November 26, 1901.

Application filed March 15, 1901. Serial No. 51,402. (No model.)

To all whom it may concern:

Be it known that I, JAMES T. COWLEY, of Boston, in the county of Suffolk and State of Massachusetts, have invented certain new and useful Improvements in Pneumatic-Despatch-Tube Apparatus, of which the following is a specification.

My invention relates to new and useful improvements in pneumatic-despatch apparatus; and its object is to provide an improved holder for holding the carriers and for bringing them into alinement with the despatch-tube for transmission.

My invention consists of certain novel features hereinafter described, and particularly pointed out in the claims.

In the accompanying drawings, which illustrate a construction embodying my invention, Figure 1 is a front elevation of the carrier-holder and a portion of the despatch-tube. Fig. 2 is a side elevation of the carrier-holder and a portion of the despatch-tube. Fig. 3 is a top plan view of the carrier-holder.

Like letters of reference refer to like parts throughout the several views.

A represents a carrier-holder journaled in the opposite side frames A' on bearings A² and held in its upright position, as shown in Fig. 2, by the spring A³, secured at its upper end to the eye A⁴ on the holder A and at its lower end to the cross-bar A⁵, connecting the opposite side frames A'. On the lower end of this holder is mounted a valve A⁶, adapted to cover the open end of the despatch-tube A⁷ when the holder A is in the position shown in Fig. 2, but to move back with the holder and uncover the open end of the despatch-tube A when the holder is in the position shown in Fig. 2, (dotted lines,) when the carrier will drop into the open end of the tube

A⁷. The holder A is provided with a handle A⁸ for moving the holder to the position shown in dotted lines, Fig. 2, for the transmission of the carriers. As shown, the despatch-tube A⁷ extends through the counter A⁹ and continues downwardly to the opposite end of the line.

Having thus described the nature of my invention and set forth a construction embodying the same, what I claim as new, and desire to secure by Letters Patent of the United States, is—

1. In a pneumatic-despatch apparatus, a despatch-tube, a movable carrier-holder, means for supporting said holder, a valve carried by said holder and normally closing said tube, and yielding means for holding said valve normally in position to close said tube.

2. In a pneumatic-despatch apparatus, a despatch-tube, a pivoted carrier-holder, means for supporting said holder, a valve carried by said holder and normally closing said tube, and a spring for holding said valve in position to close the tube.

3. In a pneumatic-despatch apparatus, a despatch-tube, a pivoted carrier-holder, means for supporting said holder, a valve carried by said holder and normally closing said tube, a spring for holding said valve in position to close the tube, and a handle for moving said holder to despatch a carrier.

In testimony whereof I have signed my name to this specification, in the presence of two subscribing witnesses, this 18th day of February, A. D. 1901.

JAMES T. COWLEY.
